UNITED STATES PATENT OFFICE.

IRA H. SPENCER, OF WEST HARTFORD, CONNECTICUT, ASSIGNOR, BY MESNE ASSIGNMENTS, TO THE SPENCER TURBINE COMPANY, A CORPORATION OF CONNECTICUT.

PRESSURE-GAGE.

1,301,983.

Specification of Letters Patent. Patented Apr. 29, 1919.

Application filed May 5, 1916. Serial No. 95,708.

To all whom it may concern:

Be it known that I, IRA H. SPENCER, a citizen of the United States, and a resident of West Hartford, in the county of 5 Hartford and State of Connecticut, have invented a new and Improved Pressure-Gage, of which the following is a specification.

My invention relates to the class of 10 devices above described and an object of my invention, among others, is to provide a portable device in which liquid is used for determining the pressure and which shall be constructed to prevent the unintentional 15 escape of the liquid.

One form of device embodying my invention, and in the construction and use of 20 which the objects herein set out, as well as others, may be attained, is illustrated in the accompanying drawings, in which:—

Figure 1 is a view in elevation of a gage embodying my invention with parts broken away to show construction.

Fig. 2 is a view in longitudinal section on 25 plane denoted by dotted line 2—2 of Fig. 1.

Fig. 3 is a detail view in cross section through my improved gage on plane denoted by dotted line 3—3 of Fig. 2.

My improved gage is so constructed that 30 liquid, as mercury, may be employed as the agent to denote the pressure, as it is provided with means for readily subjecting this liquid to the influence of atmospheric pressure, and at the same time is provided with 35 means whereby the unintentional escape of the liquid is guarded against. While my improved gage is not limited in its use to any special purpose, as it finds ready application in determining the pressure in the 40 conduits of pneumatic apparatus and especially in the hose and tools of cleaning devices, I have shown, in the drawings herein, my invention as applied to a gage that may be used for this purpose.

In the accompanying drawings, the 45 numeral 5 indicates a vacuum head containing a vacuum chamber 6. This head may be constructed of any suitable material, and I have found that rubber, not perfectly 50 rigid, but enough so to withstand any vacuum to which the device will be subjected, will satisfactorily answer the purpose, and in fact, I believe this material to be superior to many others.

A body 7, preferably of a comparatively 55 rigid material, extends through openings in both walls of the head 5, and hence through the vacuum chamber 6, the latter being thus formed into an annular chamber. The body 7, especially as to the projecting end 8 is of 60 a size and form to be received within a hose or like conduit for air, and the opposite end of the tube is adapted to receive a plate 10 having an inlet opening 9. This plate is removably secured to the body for the 65 purpose of enabling plates with inlet openings of different sizes to be used. A number of ports 11 are formed through the walls of the body 7 within the vacuum chamber 6. 70

A pressure chamber 12 and an air inlet chamber 13 are also formed in the head 5, the latter chamber having an air inlet port 14 and the former having a pressure port 15 extending between the vacuum chamber 75 and the pressure chamber. 70

Holes 16, 17 are formed through the bottom walls of the chambers 12 and 13 and necks 18, 19 extend from the head and surround said holes. A vacuum tube 20 of 80 the usual U-shape has its free ends inserted through the holes 16 and 17 and into the chambers 12 and 13. The open ends of the tube are located against the top of each of the chambers 12 and 13, so that the top of 85 each of said chambers will close and seal the open ends of the tube under normal conditions, and in order to obtain sufficient rigidity to effect this resulting purpose, a filling 21 of metal or other comparatively rigid 90 material is inclosed within the substance of the head and immediately over the open ends of the tube. A binder 22 of any substantial material may be secured around the necks 18 and 19 to attach the tube securely 95 to the head.

A support 23, preferably of some resilient 100 flexible material, as rubber, is secured to the lower end of the body to support the vacuum tube. The object of this flexible support is that it shall be movable so that the tube as a whole may be moved vertically, that is, so that its ends may be manually moved away from and automatically moved toward the tops of the chambers 12 105 and 13. The flexible and resilient support herein shown effectually accomplishes this, but I contemplate as within the spirit and

5 intent of the invention, any means of support of the vacuum tube whereby its open ends may be moved from or against the tops of the chambers 12 and 13, or, in fact, any means whereby spaces may be created between the ends of said tube and the tops of said chambers.

In the operation of the device, a plate 10 having an opening 9 of the desired size is 10 placed upon the end of the body 7 and the opposite end 8 will be inserted into the chamber or end of the hose within which the pressure is to be determined. Force applied to the support 23, by reason of its 15 flexibility and the flexibility of the bottom walls of the head 5, will move it from its normal position as indicated in dotted lines in Fig. 1, and this will cause the ends of the 20 vacuum tube to be moved away from the top of the chambers 12 and 13. The liquid, as 25 mercury, which will be contained within the tube 20 will thus be subjected to the influence of atmospheric pressure and the pressure within the chamber or hose to which the gage is attached, and the mercury will thus determine in the usual manner the relative difference between these pressures.

The ports 11 are somewhat exaggerated 30 in the drawings herein, as to size, in order to certainly show them, but it will be understood that in order to obtain the best and most accurate results, these ports will be very small.

In accordance with the provisions of the 35 patent statutes, I have described the principles of operation of my invention, together with the device which I now consider to represent the best embodiment thereof; but I desire to have it understood that the 40 device shown is only illustrative, and that the invention may be carried out by other means.

I claim:

1. A gage including a body having a 45 chamber therein, an indicating tube to contain a measuring medium and having communication with the interior of said body and also with the atmosphere, and self actuating means for closing one end of said tube to shut off communication with the chamber in said body.

2. A gage including a body having a 55 chamber therein, a U shaped indicating tube to contain a measuring medium and having one end communicating with the interior of the body and the other end communicating with the atmosphere, and self actuating means for normally closing one end of said tube to shut off communication with the chamber in said body.

3. A gage including a body having a 65 chamber therein, a U shaped indicating tube to contain a measuring medium and having one end communicating with the interior of the body and the other end communicating

with the atmosphere, and means, self actuating, to normally close an end of said tube to shut off communication with the chamber in said body, said closing means being arranged for operation to open said end. 70

4. A gage including a body having a chamber therein, an indicating tube of curved form to contain a measuring medium and having one end communicating with the interior of the body and the other 75 end communicating with the atmosphere, means for sealing an end of said tube, a tube support, and means for causing relative movement between said sealing means and end of the tube to normally seal the latter to shut off communication with the chamber in said body. 80

5. A gage including a body having a chamber therein, an indicating tube of curved form to contain a measuring medium and having one end communicating with the interior of the body and the other end communicating with the atmosphere, means for normally sealing an end of said tube to shut off communication with the 85 chamber in said body and means for securing the tube to permit the sealing and unsealing of an end thereof. 90

6. A gage including a body having a chamber therein, a U shaped indicating tube 95 to contain a measuring medium and having one end communicating with the interior of the body and the other end communicating with the atmosphere, means for simultaneously sealing both ends of said tube, and means for causing relative movement between said sealing means and the ends of the tube to effect sealing and to permit unsealing of the latter. 100

7. A gage including a body having a 105 chamber therein, a U shaped indicating tube to contain a measuring medium and having one end communicating with the interior of the body and the other end communicating with the atmosphere, a movably mounted 110 support for said tube, and a sealing member mounted to receive the ends of said tube in one position to seal them.

8. A gage including a body having a chamber therein, a vacuum chamber communicating with said body, a pressure chamber communicating with the vacuum chamber, an inlet chamber communicating with the atmosphere, a U shaped tube with its ends projecting into said pressure and inlet 115 chambers, and means for shutting off pressure from one end of said tube. 120

9. A gage including a body having a chamber therein, a vacuum chamber communicating with said chamber, a pressure 125 chamber communicating with said vacuum chamber, an inlet chamber communicating with the atmosphere, a U shaped tube having its ends extending into said inlet and pressure chambers to contact with the walls 130

of said chambers, and means for causing relative movement of said walls and tube ends to seal the latter.

10. A gage including a body having a 5 chamber therein, a vacuum chamber communicating with said chamber, a pressure chamber communicating with said vacuum chamber, an inlet chamber communicating with the atmosphere, a U shaped tube having its ends extending into said inlet and pressure chambers, the walls of which are flexible, and means for securing the tube to cause its ends to normally press against the walls of said chambers to seal the ends of 10 the tube.

11. A gage including a head having a 15 vacuum chamber therein, a body having a chamber communicating with that in the head, a pressure chamber and an air chamber communicating with said vacuum chamber and the latter chamber communicating with the atmosphere, a U shaped tube extending through the walls of said head into said pressure and air chambers, and means 20 for closing an end of said tube.

12. A gage including a head having a 25 vacuum chamber therein, a body having a fluid chamber communicating with that in the head, a pressure chamber and an air inlet chamber in said head, said chambers having flexible walls, the former chamber communicating with said vacuum chamber and the latter chamber communicating with the atmosphere, a U shaped tube extending 30 through the walls of said head and with an end located to be closed by a wall of one of the chambers into which the ends of the tube extend, and means for causing relative movement between said wall and tube end.

13. A gage including a head having a 35 vacuum chamber therein, a body having a fluid chamber and extending through said vacuum chamber, ports extending through the walls of said body into said vacuum 40 chamber, a pressure chamber and an air inlet chamber in said head, the former communicating with said vacuum chamber and the latter communicating with the atmosphere, a U shaped tube having its ends projecting 45 into said air inlet and pressure 50

chambers, and means for closing an end of said tube.

14. A gage including a head having a 55 vacuum chamber, an air inlet and a pressure chamber, said air inlet and pressure chambers each having a flexible wall, and said air and inlet chambers communicating with the atmosphere, and said pressure chamber communicating with said vacuum chamber, a body extending through said 60 vacuum chamber and having a chamber therein, a port extending through the walls of said body into said vacuum chamber, a U shaped tube having its ends projecting 65 into said air inlet and pressure chambers and with an end of said tube located to normally rest against the wall of one of said chambers, and means operatively connected with said tube and arranged to permit flexing of a wall of one of said chambers to 70 create a space between the end of said tube and a wall of said chamber.

15. A head having a vacuum chamber, a 75 pressure chamber and an air inlet chamber communicating with the atmosphere, a wall of each of said air inlet and pressure chambers being flexible, a body extending through said vacuum chamber and containing a chamber with ports extending through the wall of said body into said vacuum chamber, a U shaped tube with its ends extending 80 through the flexible walls of said air inlet and pressure chambers, and with an end of said tube located to be closed by a wall of a chamber into which the end of the tube 85 extends, and a flexible support for said tube.

16. A gage including a body having a 90 chamber therein, a vacuum chamber communicating with said chamber in the body, a pressure chamber communicating with 95 said vacuum chamber, an inlet chamber communicating with the atmosphere, a U-shaped tube having its ends extending into said inlet and pressure chambers to contact with the walls of said chambers, and means to effect and permit relative movement as between said walls and the tube whereby the ends of the tube may be sealed and unsealed.

IRA H. SPENCER.
